UNITED STATES PATENT OFFICE.

GEORGE CAWTHON, OF REDWOOD CITY, CALIFORNIA.

COMBINED LOCK AND LATCH.

Application filed March 9, 1926. Serial No. 93,481.

This invention relates to a combined lock and latch, particularly adapted for installation within swinging doors, and has for its primary object to provide means whereby the 5 latch bolt may be readily secured in projected position within its door frame keeper for thus overcoming the necessity of providing a separate lock bolt for the lock mechanism.

10 A further object is to provide a combined lock and latch of this character wherein after the latch bolt has been locked in said projected position, it will be practically impossible for the lock to be picked or the bolt 15 otherwise released other than by provision of a key constructed for use in the operation of the mechanism.

A further and important object resides 20 in the provision of such a combined lock and latch that is of relatively simple construction, but yet highly efficient in operation, the same comprising but few parts as compared with other locks now used, and these so co-related as to reduce the possibility 25 of disarrangement to a minimum and to facilitate the retraction of the latch bolt through reason of the usual hand knob, and also to facilitate the ready locking of the latch bolt, when in projected position.

30 Other objects will become apparent as the nature of the invention will become better understood, the same comprising the novel form, combination and arrangement of parts hereinafter more fully described, shown in 35 the accompanying drawings, and claimed.

In the drawings wherein like reference characters indicate corresponding parts throughout the various views:—

Figure 1 is a fragmentary outside elevation 40 of a conventional swinging door that is equipped with my improved combined lock and latch, certain portions of which are broken away, while parts thereof are disposed in cross section for purposes of clearness,

Fig. 2 is a similar view of the mechanism, the door plate and casing cover plate thereof being removed, while the door is also partly disposed in section for more clearly 50 illustrating the construction of the mechanism,

Fig. 3 is a view somewhat similar to Fig. 2, the various elements thereof being however disclosed in latch bolt locking condition,

Fig. 4 is a detail vertical section through the door and combined lock and latch,

Fig. 5 is a fragmentary horizontal section therethrough,

Fig. 6 is a fragmentary section through 60 the upper end of the mechanism, certain elements of construction being removed for more clearly disclosing the inner end construction of the sliding latch bolt,

Fig. 7 is a fragmentary vertical transverse 65 section through the center portion of the mechanism for more clearly disclosing the construction of the latch bolt locking member per se,

Fig. 8 is a sectional view taken through 70 the knob control latch bolt releasing element per se,

Fig. 9 is an inner side elevation of the inner end of the latch bolt, and

Fig. 10 is an inner side elevation of the 75 keeper plate of the combined latch bolt.

Now having particular reference to the drawing, my novel mechanism constitutes the provision of a metallic casing 5 that is so constructed as to provide three interconnecting circular portions as clearly disclosed in Figs. 1, 2 and 3. The door A is suitably mortised or pocketed adjacent the free edge thereof to receive this casing while leading from said mortise or the pocket at the upper 80 edge thereof in a direction toward the free edge of the door is a channel 6 through which the latch bolt of the device freely moves. The outer end of this channel is equipped with the usual metallic guide plate 90 7 that is formed with an opening in its center to permit the head of the bolt to slide inwardly and outwardly thereof.

At the sides of the two lowermost circular sections of the casing 5 are outwardly projecting flanges 8, the flanges of the lowermost circular section connecting as clearly shown in Figs 2 and 3. These flanges which effect the side walls of the casing facilitate the positioning of the same within the door 100 mortise or pockets, and also properly support the casing when disposed therein. The uppermost circular portion of the casing is unflanged at its sides, but is at its upper edge formed with a circular flange 9 serving for 105 the same purpose as the flanges of the circular portion.

Extending longitudinally across the outer face of the uppermost circular portion of the casing 5 are spaced parallel ribs 11—11 110

serving as a guide for the inner end of the latch bolt which is designated in its entirety by the character 12, the inner end of which is in the form of a rectangular shaped plate 13 mounted for free sliding movement between said ribs 11—11 while the outer end thereof is in the form of a conventional head 14 slidable through the opening in the channel closing plate 7, said head and said plate 14 and 13 respectively being adjustably interconnected through medium of a bolt 15 that is carried by said head and that is threaded at its inner end for threaded engagement within a threaded opening in the adjacent end of said plate as more clearly shown in Fig. 5.

The center of the casing at the upper circular portion thereof is formed with an opening 16, Fig. 5, for a purpose hereinafter more fully described, and projecting laterally inwardly from the ribs 11—11 at diametrically opposed sides of said opening, lugs 17—17, Figs 4 and 6. The under side of the plate 13 of the latch bolt 12 is so constructed as to provide longitudinal sockets 18—18 at opposite edges thereof and adjacent the outer end of the plate for the reception of the inner ends of expansible coiled springs 19—19, the outer ends of which are adapted to engage said lugs 17—17 to normally force the latch bolt outwardly to the position shown in Figs. 1, 2, 5 and 6, said springs however, permitting of the free inward sliding movement of said latch bolt when the same strikes the usual keeper in the door jamb, not shown.

The plate 13 of said latch bolt 12 is further formed with an elongated opening 20 at its inner end, the same being at all times in registration with the opening 16 in said casing 5, and through which opening is removably disposed a sleeve 21, the interior of which is square shaped for receiving the knob control shaft or spindle 22 that projects through the opposite sides of the door and is adapted for receiving the conventional knobs, here not shown.

The forward end of this sleeve 21 is also of square shape externally, and upon which is to be arranged a circular plate 23, that consists of a pair of spaced disks 24—24 interconnected at their perimeters through medium of rivet pins 25. Coiled between the disks around the squared registering openings in the center thereof is a length of spring wire 26, the ends of which are projected outwardly thereof upon opposite sides of one of the connecting rivets as clearly shown in Fig. 8. These ends of the wire are adapted to engage along opposite sides of a rib 27 formed upon the inner side of an outwardly projecting internally threaded sleeve 28 that is formed integrally with the casing 5 directly beneath the upper edge

of the central circular section of the casing 65 as clearly shown in Figs. 2, 3, 4 and 6.

The annular member 23 serves as a supporting bearing for the sleeve 21, while the spring 26 serves as a means for returning the shaft 22 and said member 23 to the position disclosed in Figs. 1, 2, 3, 4, 5 and 6 at which position the latch bolt 12 is in its outwardly projected state.

At the inner end of the latch bolt plate 13 at opposite sides of the opening 20 therein are lugs 29—29, the inner edges of which are adapted to be engaged by the opposite ends of a wing-shaped plate 30 formed upon the opposite side of the shaft receiving sleeve 21 in order that when said shaft is turned 75 in opposite directions, either end of said plate will engage against the respective lugs for retracting the latch bolt against the action of the springs 19—19.

At opposite sides of the center of the 85 middle circular portion of the casing 5 are pins 31—31, the inner opposed side ends of which are rabbeted for receiving the opposite edges of a square-shaped sliding plate 32 that is formed at one end and at its upper edge with a vertically extending finger 33, that will engage the back of the adjacent end of latch bolt plate 13 when said bolt is projected and when said plate is slid 90 upwardly between the pins 31—31 in a manner hereinafter more fully described for 95 obviously locking the latch bolt in its projected position.

The opposite sides of the finger 33—33 are formed with lateral bearing blocks 100 34—34, the inner one of which rests upon the casing 5 while the cover plate for the casing hereinafter more fully described engages against the outer one of the blocks as clearly shown in Fig. 4, said blocks serving 105 to assist the pins 31—31 in the proper support of the plate 32. The inner block on both of the blocks are formed at their upper ends with sockets 35 the socket in the block adjacent the casing 5 adapted to receive one end of an expansible coiled spring 110 36, the opposite end thereof projecting against the lowermost rib 11 hereinbefore described, said spring normally serving to maintain the plate in the position shown in 115 Fig. 2, thus permitting of the retraction of the bolt when the head 14 thereof strikes the keeper in the door frame or under action of the knob control shaft or spindle 22.

The plate 32 is formed with an opening 120 37, the upper edge of which is notched at 38 intermediate its ends while the opposite ends of the opening at the upper edge thereof are so formed as to provide pin receiving and retaining notches 39—39. Pivoted to the casing 5 directly beneath the previously mentioned sleeve 28 is the upper end of a swinging latch plate 40, the lower edge of

which is widened and notched intermediate its edges for providing a pair of fingers 41-41. Upon the outer side of said plate 40 and adjacent the edge thereof next to 5 the finger carrying edge of the plate 32, is an outwardly projecting pin 42 that is adapted to engage within the notch 39 beneath the finger 33 of the plate 32 when said plate has been forced upwardly, and 10 the latch plate swung into the position shown in Fig. 3 for maintaining the fingers 33 of said plate 32 in an upward position in back of the latch bolt 13 for retaining said latch bolt in projected position.

15 At this point, it may be well to state that the reason for the sockets in the bearing block 34-34 of the finger carrying plate 32 and the provision of the notches 39-39 at opposite sides of the opening 37 in said 20 plate is to permit this plate to be disposed reversely within the casing 5 should it be necessary to dispose the mechanism in the opposite side of the door A from that shown in the figure, such a reversal of position obviously necessitating the reversal of the 25 other elements of construction such as the latch bolt 12, sleeve 21, etc., etc.

The lower circular section of the casing 5 is formed centrally with a T-slot 43 within 30 which is adapted to be inserted a properly formed key 44, the head of which is so constructed as to first engage the lower edge of the finger carrying plate 32 when the same is turned in the opening for obviously raising said plate, and then engaging the finger 41 of the latch plate 40 beneath the pin 42 for swinging said latch plate upon its pivot to engage said pin 42 within the adjacent 35 end notch of the plate opening 37.

40 After the lock has been assembled in the door in a manner as heretofore described and as shown in the drawing, a casing cover plate 45 is disposed thereover, the same being shaped complementary to the casing

and secured thereto by reason of a locking screw 46 that passes through an opening in the cover plate, which when positioned will register with the sleeve 28 that receives the threaded shank of the screw in a manner as clearly disclosed in Fig. 4. Upon opposite 50 faces of the door are the usual ornamental lock cover plates 47-47.

It will be readily understood by reviewing the accompanying drawing and by perusing the foregoing specification, that I 55 have provided a highly novel, simple, and efficient form of combined lock and latch mechanism that is well adapted for all of the purposes designated, and even though I have shown and described the mechanism as 60 including certain detail structural elements, it is nevertheless to be understood that departures may be had without effecting the spirit and scope of the appended claim.

Having thus described my invention, 65 what I claim as new and desire to secure by Letters Patent is:—

In a combined lock and latch of the class described, a casing, a latch bolt mounted in the casing, means for normally urging 70 the latch bolt outwardly of the casing, a knob controlled spindle arranged within the casing, means carried by the spindle cooperating with the inner end of the latch bolt for retracting the same, and means for 75 automatically returning the spindle to its normal position, said means comprising a pair of spaced members mounted on the spindles, a spring coiled about the spindle and confined between the spaced members, a 80 pin projecting laterally from the casing, the free ends of the spring extending on opposite sides of the pin in engagement therewith.

In testimony whereof I affix my signature. 85

GEORGE CAWTHON.
